COMBINED ICE BAG AND FOUNTAIN SYRINGE

Wolf Sevush, Brooklyn, N. Y.

Application November 27, 1946, Serial No. 712,523

5 Claims. (Cl. 128—227.)

1

The present invention refers to an icebag and fountain syringe and refers more particularly to an article of manufacture comprising a thin, flexible, waterproof sheet gathered around a rigid neck member to constitute a closable substantially liquid tight container, the neck member being threaded and the article further comprising a threaded cap, engageable in the neck member to close the bag.

An object of the present invention is to provide an article which may be used alternatively as an icebag and as a fountain syringe.

A further object is that the article may be converted from one function to the other with a minimum of adjustment.

Another object is that, in each of its functions of icebag and fountain syringe, the article shall perform exactly as a conventional article.

Still another object is that the changeover from one function to the other shall be simple in theory and in practice so that the article may be used by people without mechanical knowledge or aptitude.

Yet another object is that the article shall be simple to manufacture with facilities at the disposal of any manufacturer of hospital and drug supplies.

In accomplishing the objects of the present invention a conventional icebag comprising a rigid neck member to which is fastened a sheet of thin, flexible, waterproof material constituting a bag body deformable from a substantially circular shape comprising a flat bottom wall and a pleated upper wall in which the neck is concentrically located, is provided centrally of the flat bottom wall with a comparatively heavy flexible rubber dome located on its interior surface and extending upward inside the neck portion. The dome is attached to the bottom wall by any convenient means such as rubber cement or vulcanizing and is downwardly open, the portion of the bottom wall peripherally inside the dome being removed so that the interior of the dome communicates with the outside of the bag. Internally of the dome and connected to the top portion thereof is located a nipple preferably of hard rubber which extends substantially for the complete interior height of the dome. The dome may be depressed and peripherally and outwardly deformed so as to cause the nipple to extend outwardly through the bottom of the bag. The nipple is provided with a tubular opening throughout its length and its top end may be closed or opened as desired by a screw threaded thereinto or by any other convenient closure means. When the passage through the nipple is closed, and the dome is undeformed and the nipple contained therein, the article may be used as an icebag or hot water bag, the dome extending into the neck, as already mentioned, so that the outer contour of the bag is identical with that of a conven-

2

tional icebag. When it is desired to use the article as a fountain syringe, the cap of the bag is removed, the plug or other closure means of the nipple passage is removed through the bag neck and the dome depressed so as to expose the nipple through the bottom of the bag. A rubber tube or the equivalent may be attached to the exposed nipple and the bag may be hung from a wall fixture such as a hook by means of a flap attached to the neck and provided with an eyelet. When so being used, the bag will assume a substantially pleated cylindrical shape with the neck at the top thereof and the dome and nipple at the bottom.

Other objects of this invention will in part be obvious and in part hereinafter pointed out. The invention accordingly consists in the features of construction, combinations of elements, and arrangements of parts which will be exemplified in the construction hereinafter described, and of which the scope of application will be indicated in the following claims. In the accompanying drawing, in which is shown one of the various possible illustration embodiments of this invention:

Figure 1 is a rear elevation, partly in section, of the article in use as a fountain syringe.

Figure 2 is a front elevation, partly in section, of the article in use as an icebag.

Referring now in detail to the drawings, the improved bag 10 comprises the substantially rigid neck portion 11 which may be conveniently internally threaded. Fastened to the neck portion 11 in conventional manner is the thin sheet 12 of flexible waterproof material which is illustrated as sheet rubber or may also be of textile material and still thinner rubber in combination. The sheet 12 is of such shape as to provide a substantially flat circular bottom wall 13 and the substantially circular pleated top wall 14 integral therewith and concentrically disposed around the neck 11. Also fastened to neck 11 is the flap 15 preferably of a similar material to sheet 12, flap 15 being provided with an eyelet 16. The cap 17 of the bag is externally threaded for engagement with neck 11 to form a watertight closure of bag 10.

Centrally of bottom wall 13 and attached to the interior surface thereof is a downwardly open dome 18 of comparatively heavy flexible material such as rubber, wall 13 of bag 10 being cut away peripherally internally of dome 18 so that the interior of dome 18 communicates with the outside of bag 10 by means of the opening 18A. Dome 18 is substantially cylindrical and has a concentric exterior foot flange 19 extending around its base portion. The side walls of dome 18 merge into the closed top portion 20 thereof and centrally of said top portion 20 is located a nipple 21 extending through top portion 20 and

attached firmly thereto so as to extend substantially axially and interiorly of dome 18 for the entire height thereof. Nipple 21 has a collar 22 which engages the underside of top portion 20 and as illustrated, a soft rubber washer 23 or the equivalent is disposed around nipple 21 above top portion 20 and held in place by a metal member 24 which may be a nut threadedly engaging nipple 21 or may be firmly fixed to nipple 21 by any other preferred fastening technique. Nipple 21 is formed with an axial passage 25, the upper portion of which is threaded, and a screw 26 provided with a washer 27 threadedly engages passage 25 to close the upper end thereof in watertight manner.

It will be noted by reference to Figure 2 that the bag 10 may rest on a flat surface and is to all outward appearance a conventional icebag, the distinguishing feature of bag 10, namely, nipple 21 mounted as described in dome 18, extending upwardly within the neck portion 11 so as not to take up any extra room.

Still referring to Figure 2 it is evident that by removing cap 17 and screw 26 and washer 27 therewith, the upper end of passage 25 is opened, and bag 10 is also in convenient position for depressing dome 18 so that it will assume the deformed shape of Figure 1. Referring now to Figure 1 nipple 21 extends downwardly through bottom wall 13 of bag 10 and a rubber tube 28 may be conveniently attached thereto when bag 10 is to be used as a fountain syringe. In such manner of use the bag 10 will be suspended by means of eyelet 16 in flap 15 from any convenient wall fixture, such as a hook, and bag 10 will assume the approximately cylindrical shape illustrated in Figure 1. In such shape of bag 10, water or other liquid 29 contained in bag 10 may pass freely through passage 25 of nipple 21 and be used in manner customary with fountain syringes. Dome 18 in Figure 1 as shown is extremely deformed, the walls thereof extending above and back inwardly over top portion 20. Such deformed shape of dome 18 may be maintained indefinitely, since the side walls in such condition and position exert a downward force on nipple 21. In such position of dome 18 nipple 21 is adapted to discharge substantially all of the water or other liquid in bag 10.

It will thus be seen, that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

What is claimed is:

1. A combined ice bag and fountain syringe comprising the combination with ice bag means comprising a rigid neck portion and thin, flexible, waterproof sheet material fastened thereto to constitute a bag body, of nipple means fastened interiorly to said body and normally located inside said neck portion and movable to a position of extending through the bottom of said bag body for the attachment of a rubber hose or the like.

2. A combined ice bag and fountain syringe comprising the combination with ice bag means

comprising a rigid neck portion and thin, flexible waterproof sheet material fastened thereto to constitute a bag body, of a comparatively heavy, flexible, substantially cylindrical dome attached to the interior surface of the bottom wall of said ice bag, said dome being downwardly open and said bottom having a passage formed therethrough peripherally inwardly of said dome, and nipple means located inside said dome, said dome being deformable so as to cause said nipple means to extend through said passage and below said bottom wall.

3. A combined ice bag and fountain syringe comprising the combination with ice bag means comprising a rigid neck portion and thin, flexible waterproof sheet material fastened thereto to constitute a bag body, of nipple means fastened interiorly to said body and normally located inside said neck portion and movable to a position of extending through the bottom of said bag body for the attachment of a rubber hose or the like, said nipple means further having a passageway formed therethrough for the passage of liquid, said nipple means further comprising screw and washer means engaging the upper end portion thereof for substantially watertight closure thereof.

4. A combined ice bag and fountain syringe comprising the combination with ice bag means comprising a rigid neck portion and thin, flexible waterproof sheet material fastened thereto to constitute a bag body, of a comparatively heavy, flexible, substantially cylindrical dome attached to the interior surface of the bottom wall of said ice bag, said dome being downwardly open and said bottom wall having a passage formed therethrough peripherally inwardly of said dome, and nipple means located inside said dome, said dome being deformable so as to cause said nipple means to extend through said passage and below said bottom wall, said nipple means further having a passageway formed therethrough for the passage of liquid, said nipple means further comprising screw and washer means engaging the upper end portion thereof for substantially watertight closure thereof.

5. A combined ice bag and fountain syringe comprising the combination with ice bag means comprising a rigid neck portion and thin, flexible waterproof sheet material fastened thereto to constitute a bag body, of a comparatively heavy, flexible, substantially cylindrical dome attached to the interior surface of the bottom wall of said ice bag, said dome being downwardly open and said bottom wall having a passage formed therethrough peripherally inwardly of said dome, and nipple means located inside said dome, said dome comprising a top portion and side wall portions and being deformable so as to cause said nipple means to extend through said passage and below said bottom wall, said side wall portions when said dome is so deformed extending above and back inwardly of said top portion.
